UNITED STATES PATENT OFFICE.

STANLEY E. BOYNTON, OF OAK PARK, ILLINOIS, ASSIGNOR TO CHARLES E. REED.

LATHE DOG.

Application filed October 17, 1924. Serial No. 744,182.

My invention relates, more particularly, to lathe dogs for use in connection with copying lathes for producing shoe lasts; and my primary object is to provide a construction of lathe dog which may be adjusted on its support into different positions to conform to different shaped heel portions of last-patterns used in such lathes, and by the use of which lathe dogs the stubs remaining on the heel portions of the last-blanks after the latter have been turned into last form, will extend in the same position relative to the upper and lower surfaces of the lasts regardless of variations in the contour of the heel portions of the patterns, such condition being highly desirable in connection with the further operation on the last-blanks to remove the stubs, which operation is commonly performed by machines provided for this purpose.

Referring to the accompanying drawings:—

Figure 1 is a broken face view of the swinging frame portion of a copying lathe for producing lasts in accordance with a pattern-last and comprising a head-stock spindle for the last-pattern equipped with my improved lathe dog. Figure 2 a broken view in side elevation of the head-stock spindle for the last-pattern blank, viewing the structure in the position shown in Fig. 1, and showing the lathe dog adjusted into different positions to conform to last-patterns having heel portions presenting different contours. Figure 3 is a longitudinal plan section of the lathe dog and its immediate supporting structure; and Figure 4, a plan view of the spindle and dog.

While my invention is applicable generally to lathe structures, I have shown it as embodied, for the purpose of illustration, in a machine of the general construction shown in the pending application of Charles E. Reed for United States Letters Patent, Serial No. 650,194, filed July 7, 1923, but not, however, with the intention of limiting it to use in such a construction.

As machines of the general construction shown, and above referred to, are commonly known, it will be sufficient to state that 5 represents a frame which, in accordance with common practice, is pivotally supported at its upper end on the frame work of the machine to extend dependently into a position 55 in which it opposes the pattern follower and the last-cutting mechanism mounted on the

frame work and commonly associated with pantographic grading mechanism for effecting the producing of lasts of different sizes from a single pattern. The frame 5 forms 60 the carrier, or support, for the last-pattern represented at 6 and the last-blank represented at 7, both of which are mounted in the frame 5 to be simultaneously rotated at the same speed, the frame 5, to this end, 65 being provided with head-stocks 8 and 9 and tail-stocks 10 and 11, respectively, for the pattern and last-blank. In the arrangement shown the frame 5 is provided with a shaft 12 driven, through gearing (not 70 shown) in a gear-case 13, on this frame, by a shaft 14 which, in turn, is driven by mechanism (not shown) on the machine. The shaft 12 is in driving engagement with the shaft 15 of the spindle of the head-stock 8 75 through the medium of gearing (not shown) in a gear-case 16 on the frame 5, and the spindles 17 of the head-stock 9 is driven from the shaft 12 by gearing (not shown) in a gear-case 12^a, also provided on this 80 frame.

In further explanation of the construction of the machine shown, it may be stated that as the pattern 6 is rotated against the pattern follower the frame 5 will swing toward 85 and away from the axis of the pattern follower, thereby moving the last-blank 7 toward and away from the axis of the cutting mechanism to produce the proper shape of last.

The head-stock 8 for the pattern is equipped with my improved lathe dog, the preferred construction of which is that disclosed and comprises a sleeve-like body 18 containing a socket 19 which fits over, and 90 is keyed to, the shaft 15 with which it operates, the sleeve 18 containing a slot 20, the rear wall of which, represented at 20^a, is of arc shape, the arc of which is described about a point in the longitudinal axis of the 95 shaft 15 and substantially in a line connecting the extremities of that part of the dog which engages the heel portion of the pattern last. The device also comprises a dog proper 21 which extends into the slot 20, its 100 rear edge portion, represented at 22, being of arc shape, the radius of the arc of which is the same as the arc described by the wall 20^a of the slot 20. The dog 21 contains an arcuate slot 23 through which, and through 105 alining openings 24 and 25 in the slotted part of the body member 18, a clamping 110

screw 26 extends, the threaded end of this screw screwing into the opening 24, the latter being threaded. The body member 18 is slotted crosswise thereof, as represented 5 at 27 at the base of one of the arms thereof and produced by forming the slot 20, to render this part of the member deflectable into clamping engagement with the dog 21 when the screw 26 is tightened, for holding the 10 dog in adjusted position on the member 18. The outer end surface of the dog is provided with teeth 28, curved as shown, to penetrate the end of pattern at its heel portion as shown in Fig. 1.

15 By forming the parts of the head-stock 8, as shown and described, the dog 21 may be tilted into various positions of adjustment on the member 18 to cause its teeth-equipped portion to conform to the heel portions of 20 patterns having different contours at their rear end surface.

The provision of the curved contacting surfaces 20^a and 22 as described which are in mutual contact in the various adjustments 25 of the dog for different forms of heels, compels the dog, in the tilting thereof to conform to the heel of a pattern-last introduced into the lathe between the head and tail stocks, to move in such a predetermined path 30 that a point midway between the points of engagement of the teeth 28 with the last, and which is necessarily in the axis of rotation of the last, does not depart from the axis of the spindle because the transverse axis 35 about which the dog turns in the bearing surface 20^a is located at a point in the last itself and which is in the line about which it is desired to revolve the last. This point in the last, or speaking more concretely, this 40 material point in the last retaining its position relatively to the axis of the spindle during the adjustments of the dog, it follows that all points in the last will retain their positions relatively to the axis of the 45 spindle or the axis of rotation of the last, and that no tilting of the last will take place during the adjustments of the dog to the particular contour of the heel portion of the last introduced into the machine, and 50 thus the stubs produced on the last-blanks, the one produced on the last 7 being represented by dotted lines at 29, are in the same position relative to the upper and lower surfaces of the formed lasts, with the known 55 advantages.

In this connection it may be stated that while the dog as shown is unprovided with any part, such as a spur, projecting beyond a line connecting the extremities of its teeth, the dog, without departing from the spirit 60 of my invention, may be provided with such a projecting part, provided such part does not interfere with the centering of the adjustment according to the curvature of the heel-engaging portion of the dog; thus a

projecting part of such small size that the wood of the heel into which such part projects would readily "give", in making such adjustment or one of larger proportions, provided the heel portion of the last is preliminarily recessed to loosely receive it, may be provided on the dog, if found desirable, without departing from my invention, it being my intention that the recital in the claims appended hereto that the dog is "free of any projecting part, which in the application of the last thereto would interfere with the centering of the adjustment according to said curvature about said point" be not construed to exclude a dog provided with a projection provided such projection does not interfere with the centering of the adjustment of the dog according to its curvature in the application of a last thereto.

While I illustrated and described a particular construction embodying my invention, I did not wish to be understood as limiting it thereby, as the same may be variously modified and altered without departing from the spirit of the invention.

What I claim as new, and desire to secure by Letters Patent, is:

1. A spindle for a last-lathe stock for engaging the heel portion of a pattern last comprising a body portion and a dog portion adjustable thereon, one of said portions having an arc-shaped surface extending generally crosswise of the spindle, the curvature of said surface being in a direction crosswise of the spindle and concentric with a point substantially in a line connecting the extremities of that portion of the dog which engages the heel portion of the pattern last, said dog being free of any projecting part which, in the application of the last thereto, would interfere with the centering of the adjustment according to said curvature about said point, the other of said portions engaging with, and movable along, said surface.

2. A spindle for a last-lathe stock for engaging the heel portion of a pattern last comprising a body portion, a dog portion adjustable thereon, one of said portions having an arc-shaped surface extending generally crosswise of the spindle, the curvature of said surface being in a direction crosswise of the spindle and concentric with a point substantially in a line connecting the extremities of that portion of the dog which engages the heel portion of the pattern last, said dog being free of any projecting part which, in the application of the last thereto, would interfere with the centering of the adjustment according to said curvature about said point, the other of said portions engaging with, and movable along, said surface, and means for securing said dog to said body portion in adjusted position thereon.

3. A spindle for a last-lathe stock for engaging the heel portion of a pattern last comprising a body portion containing a slot extending lengthwise of the spindle, a dog 5 extending into said slot and adjustable therein, said slot and dog having engaging surfaces one of which is arc-shaped and extends generally crosswise of the spindle with its curvature in a direction crosswise 10 of the spindle, said dog containing a slot, and means extending into said slot for securing said dog in adjusted position on said body portion, said slot in said dog being elongated in a direction crosswise of the 15 axis of said spindle to permit movement of said dog on said body portion in the adjusting of said dog, and said curved surface being concentric with a point substantially in a line connecting the extremities of that 20 portion of the dog which engages the heel portion of the pattern last, said dog being free of any projecting part which, in the application of the last thereto, would interfere with the centering of the adjustment 25 according to said curvature about said point.
4. A spindle for a last-lathe stock for engaging the heel portion of a pattern last comprising a body portion and a dog adjustable thereon, said body portion and dog 30 having mutual contacting arc-shaped surfaces extending generally crosswise of the spindle, the curvature of said surfaces being in a direction crosswise of the spindle and said arc-shaped surfaces being concentric 35 with a point substantially in a line connecting the extremities of that portion of the dog which engages the heel portion of the pattern last, said dog being free of any projecting part which, in the application of the last thereto, would interfere with the centering of the adjustment according to 40 said curvature about said point.
5. A spindle for a last-lathe stock for engaging the heel portion of a pattern last 45 comprising a body portion, a dog adjustable
- thereon, said body portion and dog having mutual contacting arc-shaped surfaces extending generally crosswise of the spindle, the curvature of said surfaces being in a direction crosswise of the spindle and said arc-shaped surfaces being concentric with a point substantially in a line connecting the extremities of that portion of the dog which engages the heel portion of the pattern last, 50 said dog being free of any projecting part which, in the application of the last thereto, would interfere with the centering of the adjustment according to said curvature about said point, and means for securing said dog to said body portion in adjusted position 55 thereon.
6. A spindle for a last-lathe stock for engaging the heel portion of a pattern last comprising a body portion containing a slot extending lengthwise of the spindle, the rear wall of said slot being of arc-shape and extending generally crosswise of the spindle with the curvature of said wall being in a direction crosswise of the spindle, a dog 60 extending into said slot and adjustable 65 therein, said dog having a curved surface contacting with said curved rear wall of said slot and containing a slot, and means extending into said slot for securing said dog in adjusted position on said body portion, said slot in said dog being elongated in a direction crosswise of the axis of said spindle 70 to permit movement of said dog on said body portion in the adjusting of said dog, and said curved rear wall of the slot in said body portion being concentric with a point substantially in a line connecting the extremities of that portion of the dog which engages the heel portion of the pattern last, 75 said dog being free of any projecting part which, in the application of the last thereto, would interfere with the centering of the adjustment according to said curvature about said point.
